UNITED STATES PATENT OFFICE.

W. GLENN TAYLOR, OF CINCINNATI, OHIO.

APPARATUS FOR SIPHONING OR DRAWING OFF WATER, STARCH-LIQUOR, AND IMPURITIES FROM TUBS OR TANKS.

SPECIFICATION forming part of Letters Patent No. 247,433, dated September 20, 1881.

Application filed August 4, 1881. (No model.)

To all whom it may concern:

Be it known that I, W. GLENN TAYLOR, a citizen of the United States, residing at Cincinnati, in the county of Hamilton and State 5 of Ohio, have invented a new and useful Apparatus for Siphoning or Drawing Off Water, Starch-Liquor, and Impurities from Tanks, of which the following is a specification.

My invention relates to improvements in apparatus for siphoning or drawing off water and starch-liquor, and freeing the said starch-liquor from all impurities. I attain these objects by means of the apparatus illustrated in the accompanying drawings, in which—

15 Figure 1 is a plan of tub with discharge-cocks, sample-cocks, and a bearing-off trough at the bottom. Fig. 2 is an elevation of same, showing movable hose. Fig. 3 is a cross-section of the same, showing bottom valve.

20 Similar letters refer to similar parts throughout the several views.

A is a tub of any shape desired. B is a valve in bottom of tub A. C is a lever, with cord attached, for operating valve B. D are discharge-cocks in the tub A. E are test or sample cocks in the lower part of the discharge-cocks D. F is a movable hose with a funnel at top, that can be attached to any of the discharge-cocks D by means of the strap G. H 25 is a trough in the floor, through which the water, starch-liquor, or the impurities may be drawn off, as desired, to a receptacle prepared for the purpose.

A portion of the starch-liquor, after undergoing the usual process of maceration in alkaline solution, is placed in the tub A with a certain proportion of water, as desired. It is then agitated and allowed to stand long enough for the starch, bran, fiber, &c., to begin to settle 35 to the bottom. The water is then drawn off from the top, as the material settles, by means

of the discharge-cocks D. The proper time for drawing off the water is ascertained by drawing a small portion of the liquid through the test or sample cocks E. After the water first 45 added is drawn off, more water is let into the tank A and the whole mass agitated again, and as the impurities settle to the bottom of the tub (the time of which settling is shown by samples taken from the sample-cocks E) the 50 starch-liquor is drawn off from the top through the discharge cocks D, movable hose F, and trough H into a reservoir prepared for it. This process is repeated until all impurities are removed from the starch-liquor. The bran and 55 other impurities remaining in the tub are then drawn off through the valve B.

This process of starch-making is known among starch-makers as "siphoning," and other starch-makers draw the starch-liquor 60 from the tub by means of a siphon or through holes in the tub, stopped by plugs.

By the use of my improved apparatus the operation of starch-making can be performed much more rapidly and economically than by 65 the old methods of siphoning or by drawing off through holes with plugs, and prevents any loss of the starch-liquor.

What I claim as my invention, and desire to secure by Letters Patent, is—

The combination and arrangement, in a tub or tank, of the discharge-cocks D, test or sample cocks E, movable hose F, and strap G, valve B, and lever C, for siphoning or drawing off water, starch-liquor, and impurities from 75 a tub, as set forth in the foregoing specification.

W. GLENN TAYLOR.
